MICHAEL G. HELM, OF STREETER, NORTH DAKOTA.

RAIL-JOINT.

1,108,841.

Specification of Letters Patent. Patented Aug. 25, 1914.

Application filed October 30, 1913. Serial No. 798,303.

To all whom it may concern:

Be it known that I, MICHAEL GEORGE HELM, a subject of the Emperor of Germany, residing at Streeter, in the county of Stutsman and State of North Dakota, have invented certain new and useful Improvements in Rail-Joints, of which the following is a specification, reference being had therein to the accompanying drawing.

10 This invention relates to rail joints, and has for its object to provide means, in a manner as hereinafter set forth for connecting the abutting ends of a pair of rails together and for further connecting the 15 said abutting ends to a tie, at the same time permitting for the expansion and contraction of the rails due to the changes in temperature.

Further objects of the invention are to 20 provide a rail joint, which is simple in its construction and arrangement, strong, durable, efficient in its use and conveniently set up.

With the foregoing and other objects in 25 view, the invention consists of the novel construction, combination and arrangement of parts as hereinafter more specifically described and illustrated in the accompanying drawings, wherein is illustrated an embodiment 30 of the invention, but it is to be understood that changes, variations and modifications can be resorted to which come within the scope of the claim hereunto appended.

In the drawings wherein like reference 35 characters denote corresponding parts throughout the several views:—Figure 1 is a side elevation partly in section of a pair of rails having the opposing ends thereof connected together. Fig. 2 is a sectional 40 plan, of a pair of rails having the opposing ends connected together, and Fig. 3 is a cross section view through the joint.

Referring to the drawings in detail, 4 denotes a tie for supporting the ends of a pair 45 of rails 5, 6. Each of said rails has its web 7 at one end enlarged as at 8, and formed integral with the enlarged portion 8 of the web 7 is a longitudinally extending rectangular tongue 9, which projects from the 50 terminus 10 of the rail. Each of said rails 5, 6, has its web 7 at the other end formed with an elongated longitudinally extending enlargement 11, which is flush at its free end with the terminus 12 of the rail, and

the width of said enlargement is the same 55 as the head 13 of the rail, the said enlargement 11 extending from the base 14 of the rail to the head 13 and is flush with the sides of the head. The enlargement 11 is cut away to provide a longitudinally extending 60 pocket 15 for the reception of the tongue 9, the latter being provided with a vertically disposed opening 16, the lower portion thereof tapering as at 17. The base 14 of the rail is formed with a tapering opening 18, 65 which registers with the tapering portion 17 of the opening 16. The head 13 of the rail is formed with an opening 19, having a flaring upper portion 20 to form what may be termed a countersink. The opening 19 70 registers with the top of the opening 16. Extending down through the openings 19, 16 and 18, is a fastener member 21, having a wedge-shaped lower portion 22 and a head 23, which when the fastener member is secured in position is mounted against the countersunk portion 20 whereby the head will be flush with the tread of the rail. The fastener member 21 is in the form of a spike 75 and extends down into the tie 4, whereby 80 the interengaging ends of the rails 5, 6, are coupled together and secured to the tie 4. The fastener member does not snugly engage the wall of the opening 16, nor does the tongue 9 extend to the inner wall of the 85 pocket 15, under which conditions clearance is made for contraction as well as expansion of the rails.

What I claim is:—

A rail joint comprising the combination 90 with a pair of opposing rails, one of which being provided with a pocket and the other with a tongue, the said tongue extending into said pocket, and a fastener member extending down through the head and base 95 of one rail and through said tongue and being adapted to engage in a tie for connecting together the opposing ends of the rails and securing the same to the tie, said fastening member having its head countersunk in the head of said rail and its lower portion formed substantially wedge-shape. 100

In testimony whereof I affix my signature in the presence of two witnesses.

MICHAEL G. HELM.
